UNITED STATES PATENT OFFICE.

AXEL M. PETERSON, OF DENVER, COLORADO.

ANTICREEPER-RAIL AND TIE-PLATE CONSTRUCTION FOR RAILWAYS.

Application filed November 10, 1927. Serial No. 232,832.

My invention relates to improvements in anticreeper rail and tie plate construction for railways.

The main object of the invention is to provide an improved rail and tie plate construction, whereby creeping of the rails on the cross ties, on any grade or under any load is prevented.

Further to provide a tie plate having a plurality of upwardly projecting parallel teeth or ribs, and a rail having corresponding recesses formed in its base flange to receive said teeth or ribs, the tie plate being also formed with spike-receiving apertures, whereby, when the rails are laid upon the plates and spiked to the cross ties, the heads of the spikes engaging the rail flange in the usual manner, the plates are thereby immovably secured to the ties and the rails are clamped against the plates, the teeth of the plates engaging the corresponding recesses in the rails, thus preventing creeping of the rails under any conditions of load or grade. These objects are accomplished by the construction embodied in the accompanying drawings in which,

Fig. 1 is a vertical transverse sectional view through a rail and tie plate constructed in accordance with my invention, said rail and plate being spiked to a cross tie.

Fig. 2 is a longitudinal sectional view through the plate and the base portion of the rail.

Fig. 3 is a perspective view of the improved tie plate, looking at the upper side thereof.

Fig. 4 is a perspective view of the tie plate, looking at the under side thereof.

Fig. 5 is a bottom plan view of a portion of a rail embodying the improved construction.

In the present practice of track construction for railways, the tracks or rails rest either directly upon the ties or upon metal plates which are placed on the ties, and are secured to the ties by spikes which pass through holes in the plates, the heads of the spikes engaging the rail flange. Such method, however, permits creeping of the rails under the rotary action of the car wheels, particularly on heavy grades, or under the frictional engagement of the wheels with the rails when the brakes have been applied, whereby the fish plates connecting the adjoining ends of the rails are frequently

broken thus permitting the connected rails to be drawn apart or disconnected. The construction embodied in the present application, however, positively eliminates this disadvantage by providing a locking connection between the rails and the tie plates, as will now be particularly described.

Referring to the accompanying drawings, the letter A designates the improved tie plate which is rectangular in form and about ten inches long by about seven inches wide. The upper side of this plate, near one of its short edges, is formed with a vertically disposed rib 1, which extends the full width of the plate and is about a fourth of an inch high. The inner face of this rib forms an abutment shoulder for one edge of the rail flange, and from this shoulder the upper face of the plate has a slight downward inclination to its opposite end edge, as clearly shown in Fig. 1. The outer side of the rib inclines down to the face of the plate, as shown, from which point the face of the plate has a slight downward inclination to the adjacent short edge. A plurality of longitudinally disposed teeth or projections 2 are formed on the upper face of the plate and midway of its length, these teeth being relatively long and of greater width than the spaces between them. They are preferably rounded in transverse sectional outline and their ends are beveled at an angle to the face of the plate. Transverse grooves or channels 3 are formed in the face of the plate adjoining the ends of the teeth 2, and square spike-receiving holes 4 and 5 are formed through the plate, the holes 4 being cut through the abutment rib 1 and so that the inner faces of the said holes are inside the line of the inner face of the rib, as shown most clearly in Fig. 3. The channels 3 are to receive any dirt or grit that may collect between the teeth of the plate and the rail grooves, and carry it off.

The under side of the plate is formed with two transverse parallel shallow channels 6 and the end portions of the plate are reduced in thickness as shown at 7, and the channels 6, and the reduced thickness 7 define three flat parallel bearing faces 8, 9 and 10, the middle face 9 being of less width than the faces 8 and 10, and these faces become slightly embedded in the tie under the weight imposed upon the plate and the plate is thus more evenly seated on the tie than would be

100

110

the case if the bottom of the plate were perfectly flat. In connection with the improved tie plate above described, I employ a rail 11, which in all respects is identical with rails in present use with the exception that the bottom face of its base flange is formed centrally of its width with transverse grooves or recesses 12 to receive the teeth or ribs 2 on the tie plate. These grooves 12 are rolled into the rail in the process of its manufacture, and extend throughout the length of the rail and are slightly longer than the teeth 2, their ends being inclined to correspond to the inclined ends of the said teeth 2. The ends of the rails are cut by gauge or so that when the ends of two rails join on a tie plate there will be no break in the continuity of the grooves 12, and the two rails will join and fit down on the teeth 2, the same as a single rail. The inclined upper faces of the track plates will cause the two rails to incline slightly toward each other, as will be understood by reference to Fig. 1.

In practice the tie plates are placed upon the ties, and the rails are then laid upon the tie plates so that the teeth on the plates engage the grooves in the rails. Spikes 13 of the usual type are then driven through the holes 4 and 5 in the plates, and into the tie, the heads of the spikes engaging the rail flange. Thus the plates are immovably secured to the tie, and the rails are immovably secured to the plates by reason of the engagement of the teeth 2 on the plate with the grooves 12 in the rail flange, and creeping of the rails on the plates is thereby prevented, resulting as frequently happens in the breaking of the fish plates which connect the rails, with the possible serious consequences due to such an accident, together

with the time and expense necessary in repairing such damage.

Having described my invention, what I claim as new and desire to secure by Letters Patent, is:—

1. In mechanism of the character described, the combination of a tie, a tie plate thereon, having spike receiving apertures, a row of elongated teeth, parallel channels adjoining the ends of said teeth and an abutment rib; and a rail resting on said plate and against said abutment rib, spikes driven through the holes in said plate to secure the plate to the tie and the rail upon the plate, said rail having grooves to receive said elongated teeth, whereby creeping of the rail on the plate is prevented.

2. As a new article of manufacture, a railway tie plate provided on its top side with an abutment rib, a row of elongated teeth extending at right angles to said rib, parallel channels extending respectively along the ends of said teeth, and spike-receiving holes, in combination with a rail having spaced elongated grooves in its base flange to receive said teeth, when the rail is laid on said plate and against said abutment rib, whereby endwise movement of the rail on the plate is prevented.

3. A railway tie plate having a central row of projecting teeth, channels being formed along the ends of the teeth, an abutment rib extending at right angles to said teeth, and raised bearing surfaces on the bottom of said plate, said plate having pairs of spike receiving holes, one pair of said holes being cut through said abutment rib.

In testimony whereof, I affix my signature.

AXEL M. PETERSON.
